UNITED STATES PATENT OFFICE.

BUELL S. BURNETT, OF JACKSONVILLE, FLORIDA.

PERMUTATION-LOCK.

1,136,653.

Specification of Letters Patent. Patented Apr. 20, 1915.

Application filed June 1, 1914. Serial No. 842,192.

To all whom it may concern:

Be it known that I, BUELL S. BURNETT, a citizen of the United States, residing at Jacksonville, in the county of Duval and State of Florida, have invented new and useful Improvements in Permutation-Locks, of which the following is a specification.

The present invention relates to permutation locks, and it proposes certain herein-
10 after-described improvements in, or in connection with, the construction, arrangement and mounting of the tumblers and their operating means or devices, whereby the lock as a whole is materially simplified, with a corresponding reduction in cost of manu-
15 facture, the manipulation of the tumblers is facilitated and, at the same time, reduced to a minimum, and the range of adjustment or change in the combination in-
20 creased to a very considerable extent.

Also, the invention contemplates an improved lock, having the afore-mentioned features, which is capable of more or less general use, instead of being restricted to
25 one or more specific applications.

An embodiment of the invention is illus-
trated in the accompanying drawing, where-
of:

Figure 1 is a front elevation of the lock;
30 Figs. 2 and 3 are rear elevations, with the back plate omitted and showing the bolt in projected and retracted positions, respectively; Figs. 4 and 5 are transverse sections taken at right angles to each other, on lines
35 4—4 and 5—5, Fig. 3, respectively; Fig. 6 is a composite perspective view, showing the various elements of the lock; Figs. 7 and 8 are front and rear elevations, respectively, showing alternative constructions; and Fig.
40 9 is a part-sectional side elevation, showing a further modification.

Referring more particularly to said drawing, 10 indicates the case of the lock, and 11 and 12 the front and back plates, respec-
45 tively. These parts may have any desired size and shape, and are here shown as circular, the part 10 having formed therethrough an opening or passage 13 for the sliding bolt 14. The front plate 11 and the case are
50 integrally connected, and the former is located some distance behind the front edge of the said case, so as to coact therewith in producing a circumferential seat or shoul-
55 der 15 for the reception of the edge of the rotatable dial-plate 16, which latter is dis-
posed against the face of plate 11 and is

provided with a central hub or stem 17 that projects inwardly through an opening 18 in that plate. The rear portion of the case is recessed to produce a similar, circumferential seat or shoulder 19, which receives the edge of the back plate, that plate being removably secured in place by screws 20 or other suitable fasteners. The edges of the two plates 12 and 16 fit closely against the outer or peripheral walls of their respective seats 19 and 15, and since the opening 18 in the plate 11 is completely covered by the dial, insertion of a tool from the front of the lock through said opening for the purpose of manipulating the hereinafter-described tumblers is rendered impossible.

The afore-mentioned bolt 14 is preferably provided upon its rear face, at the outer end thereof, with a short, longitudinal lug 21, 75 while its inner portion is slidably fitted in a guide opening 22 formed in an annular boss 23 and is recessed or cut away in order to avoid interference with the dial stem 17, the said boss being formed within the in-
80 terior of the case and having its inner peripheral wall coinciding with that of the opening 18. The said bolt is further pro-
vided upon its rear face with a central, triangular lug 24, and it is normally held 85 in retracted position through the agency of a spiral spring 25 which encircles boss 23 and is disposed in the space between the latter and an annular seat or shoulder 26, one end of said spring being connected to 90 the bolt, and the other end to the wall of said seat.

In the construction illustrated, which, for present purposes, may be considered as preferred, three tumblers 27, 28 and 29 are em-
ployed, these tumblers being subsequently referred to in the order in which they are manipulated during the unlocking opera-
tion. The first and second tumblers 27 and 28 are in the form of flat metal rings, as 100 shown in Fig. 6, which are provided at their outer edges with notches 30 and 31, and at suitable points on their inner edges with pairs of lateral fingers 32 and 33, the fingers 32 on tumbler 27 projecting radially inward, 105 while the fingers 33 on tumbler 28 are so bent as to project first inwardly and then rearwardly. The third or last tumbler 29 is constituted by a flat disk formed with an inwardly-extending V-shaped peripheral 110 notch 34 and, upon its rear face, with a pair of fingers 35 which extend beyond the pe-

riphery of the disk and are designed for engagement with the fingers 33 on tumbler 28, as hereinafter explained. The diameter of the tumbler 29 is sufficiently small to enable it to be encircled, so to speak, by the annular tumblers, as shown in Figs. 2 and 3.

In assembling the parts, the edge of the tumbler 27 is, first of all, fitted in or against the seat or shoulder 26 in the case, with its notch 30 in position to receive therein the inner end of the bolt lug 21, after which there is snugly fitted in a second annular seat or shoulder 36 formed in said case a metal retaining ring 37 of angle section, having a notch 38 through which said lug likewise extends, the inner or rear wing of this ring projecting across the adjacent face of tumbler 27. The said ring itself thus constitutes a seat which receives the edge of the tumbler 28, the latter being so arranged as to bring its notch 31 in register with the notches 30 and 38. The dial plate 16 is then disposed against the front plate 11, with its edge fitting in seat 15 and its stem 17 projecting through opening 18. The tumbler 29 is then fitted in the open central portion of tumblers 27 and 28, with its notch 34 in position to receive the triangular lug 24 on the bolt, this tumbler likewise being provided with an annular stem 39, which is formed upon its inner face concentric with a central opening 40, the wall of which coincides with the inner stem wall. The two stems 17 and 39 have exactly the same external and internal diameters, and, in consequence of this fact, will accurately aline with each other, to admit of their being connected together by a short screw 41 which is inserted through the opening 40 and stem 39 into the interior or bore of stem 17, but whereas the inner wall of the latter stem is threaded for engagement with the threads of the screw, the corresponding wall of the tumbler stem is plain or uncut, so as to permit the necessary rotation of the tumbler relative to the screw, the head of the said screw overlapping said tumbler. To prevent relative movement between said stems, the end faces of the same are formed with interlocking clutch teeth 42 and 43 which engage in the usual manner.

The setting of the tumblers is effected by manipulation of the rotatable dial plate 16, as will be understood, and to facilitate such action, the said plate may be provided either with a central knob or handle 44, or with depressions 45 for receiving the tips of the fingers, or with both; (see Figs. 1 and 7). The outer face of this plate is graduated in the usual manner, as shown in said figures, and the front wall of the case is provided with a suitable indicating point 46, with which the graduations are adapted to interchangeably aline.

In operating the lock, assuming that the

parts are in the positions represented in Figs. 3 and 4, with the bolt retracted, a turn of the dial in either direction will first cause rotation of the tumbler 29, whereupon one or the other of the inclined side walls of its notch 34, (according to the direction of such rotation), will ride against the inner, or V-shaped lug 24 on said bolt and will thus force the latter outwardly of the opening 13 in the case, while the outer lug 21 will, in like manner, be withdrawn from the notches 30 and 31 in the tumblers 27 and 28, and, also, from the notch 38 in the retaining ring 37. As the dial and the tumbler 29 continue their rotary movement, the ends of the fingers 35 are ultimately caused to engage the depending fingers 33 on the second tumbler 28, whereupon the latter is likewise caused to rotate, its notch 31 being thus moved out of alinement with lug 21. Further rotation of said parts will finally bring the terminals of fingers 33 into engagement with the fingers 32 on tumbler 27, which, in turn, will be caused to rotate and to move its notch 30 out of alinement with lug 21. The bolt will then be maintained in its projected position, and cannot be retracted until the notches 30, 31 and 34 are again brought into alinement with their respective projections. To effect the withdrawal of the bolt, assuming that a definite combination has been determined upon, the operation is, of course, the reverse of that just described, and is, in brief, as follows:—The dial is first rotated, either to the right or to the left, according as the particular combination calls for, until the figure thereon corresponding to the first figure of the combination is opposite the indicating point 46. This rotation is transmitted from the dial directly to the tumbler 29, and thence, successively, to the tumblers 28 and 27, the notch 30 in the latter tumbler being brought into alinement with the outer lug 21 exactly at the moment when the aforesaid figure on the dial alines with the indicating point. The rotation of the dial is then reversed and continued until the dial figure corresponding to the second figure of the combination is alined with the indicating point, at which time the notch 31 in tumbler 28 is brought into alinement with lug 21 and, consequently, into registration with notches 30 and 38, the tumbler 27 first set remaining stationary owing to the fact that the fingers 33 move away from, instead of toward, the fingers 32, due to the reversed direction of rotation. Finally, the dial is again rotated in the same direction as during its initial actuation, until the figure thereon corresponding to the third and last figure of the combination alines with the indicating point, thereby bringing the notch 34 in tumbler 29 opposite the inner projection 24 on the bolt, whereupon the said bolt is automatically forced

inward by the action of its spring 25, the tumbler fingers 35 releasing the fingers 33 on tumbler 28 and leaving the latter idle.

Owing to the provision of the coacting 5 series of clutch teeth 42 and 43 on the parts 17 and 39, it will be apparent that the dial and the main tumbler 29 are securely coupled together when screw 41 is tightened, so that during the continuance of any given 10 combination, they occupy relatively fixed positions. On the other hand, such positions may be varied at will by simply loosening the screw and moving either of the two parts relatively to the other, the screw being 15 thereafter re-tightened in order to effect the coupling. Each change in the relative positions will, however, necessitate a new combination, as will be obvious, and since the 20 number of such changes depends upon the number of clutch teeth, by making the said teeth narrow and disposing them close together an extremely wide range of adjustment is obtained, and the combination may be changed as often as desired, without 25 danger of repeating. If, however, it is considered advisable, for any reason, to make use of a single fixed or unchanging combination, the adjustable and detachable connection between the operating tumbler and 30 the dial may be replaced by a permanent connection, such as shown in Fig. 9, wherein the stem 17' of the said dial is solid, instead of hollow, and the tumbler 29', which is perfectly flat, is riveted directly against 35 the stem end.

While a single bolt is ordinarily sufficient for all practical purposes, the lock may be readily converted into a two-bolt construction, if desired, without requiring the use 40 of more than a single additional element, or necessitating any change in the operation, which remains the same as before, and in such case the connection between the operating tumbler and the dial may be either fixed, 45 or adjustable and detachable, according as a single permanent combination or a changeable combination is to be utilized. A construction of this character is represented in Fig. 8, in which a second bolt 14', in all 50 essential respects the counterpart of bolt 14 is arranged diametrically opposite that bolt, its outer and inner lugs 21' and 24' coöperating with notches in the tumblers located diametrically opposite the previously - de- 55 scribed notches therein and being substantial counterparts of the same, such of the duplicated parts or features as appear in the figure specified being indicated by the same numerals, equipped with the prime 60 mark, as are applied to the corresponding first-described parts or features. The same combination will, therefore, release both bolts, but to insure lug 21' entering only the 65 notches for which it was intended, it and its coöoperative notches 30' and 31' are made

larger than the lug 21 and the notches 30 and 31, as shown.

In all forms of the invention it is to be noted that during manipulation of the dial the V-shaped or triangular lug 24 on the bolt is designed to travel along the peripheral edge of the central or disk tumbler 29, thereby preventing the outer lug 21 on the bolt from entering the notches in the ring tumblers, or either of them, until the setting 75 of the tumblers has been completed. In this way, it is impossible for the operator to "feel" the notches in the tumblers when the notches are brought opposite the lug 21, so that no assistance is thus given to an unauthorized or improper manipulation of the lock to open the same. 80

I claim:—

1. In a permutation lock, the combination, 85 with a case, and a bolt slidably mounted therein and provided with lateral projections; of a pair of rotatable, annular tumblers arranged within said case in juxtaposed, concentric relation; a rotatable disk tumbler encircled by the annular tumblers, 90 each of said tumblers having a peripheral notch adapted to receive the adjacent projection; an operating element rigidly connected with the disk tumbler and free of connection with the annular tumblers; and co- 95 acting means provided upon said tumblers for transmitting rotary movement from one to another.

2. In a permutation lock, the combination, 100 with a case, and a bolt slidably mounted therein and provided with outer and inner lateral projections; of a plurality of rotatable tumblers arranged within said case and having each a peripheral notch adapted to be brought into alinement with the outer 105 projection; a smaller, rotatable tumbler arranged within said case in juxtaposition to the first-named tumblers and having a peripheral notch adapted to be brought into alinement with the inner projection; an operating element rigidly connected with the last-named tumbler; and coacting means 110 provided upon said tumblers for transmitting rotary movement from one to another.

3. A permutation lock comprising a case; 115 a bolt slidably mounted therein; a plurality of tumblers controlling the movement of said bolt, one of said tumblers being provided with an annular series of teeth; co- 120 operating means provided upon said tumblers for transmitting movement from one to another; an operating element having an annular series of teeth for adjustable engagement with the first-named series; and a member detachably coupling said operating 125 element and toothed tumbler together.

4. A permutation lock comprising a case; 130 a bolt slidably mounted therein; a plurality of tumblers controlling the movement of said bolt, one of said tumblers being pro-

vided with an axial stem formed at its free end with a series of teeth; coöperating means provided upon said tumblers for transmitting movement from one to another; 5 a rotary operating element provided upon its inner face with a stem coaxial with the first-named stem and having the free end thereof formed with a series of teeth adjustably engaged with the first-named teeth; 10 and a member detachably engaged with said stems for coupling said operating element and toothed tumbler together.

5. In a permutation lock, the combination, with a case, and a bolt slidably mounted 15 therein and provided with lateral projections; of a pair of rotatable tumblers arranged within the case and provided, each, with a pair of opposed fingers, the fingers on one tumbler being bent at right angles to 20 those of the other tumbler, to engage the same during the rotation of the first-named tumbler; a tumbler having a pair of radially projecting fingers adapted to engage the fingers on said first-named tumbler, to rotate the same, said tumblers being provided 25 with notches for the reception of said projections; and a rotatable operating element connected to the last-named tumbler.

6. In a permutation lock, the combination, with a case, and a bolt slidably mounted 30 therein and provided with lateral projections; of a pair of rotatable, annular tumblers arranged in juxtaposed, concentric relation within said case and provided, each, upon its inner periphery, with a pair of 35 opposed fingers, the fingers on one tumbler being bent at right angles to those of the other tumbler, to engage the same during the rotation of the first-named tumbler; a 40 rotatable disk tumbler encircled by said annular tumblers and provided with a pair of radially-projecting fingers adapted to engage the fingers on the first-named annular tumbler, to rotate the latter, each of said tumblers having a peripheral notch adapted 45 to receive the adjacent projection; and a rotatable operating element connected to said disk tumbler.

In testimony whereof I have hereunto set my hand in presence of two subscribing 50 witnesses.

BUELL S. BURNETT.
